UNITED STATES PATENT OFFICE.

JOHN LONDEAU, OF CORNWALL, ONTARIO, CANADA.

FURNACE.

Application filed January 25, 1922. Serial No. 531,750.

To all whom it may concern:

Be it known that I, JOHN LONDEAU, a subject of the King of Great Britain, and resident of the town of Cornwall, in the 5 Province of Ontario and Dominion of Canada, have invented certain new and useful Improvements in Furnaces, of which the following is a specification.

This invention relates to improvements 10 in furnaces, and the objects of the invention are to effectively utilize the heat units of the products of combustion and render the same available for heating purposes with air or otherwise, to so absorb the heat 15 units from the products of combustion that the said products of combustion will pass to the uptake or smoke pipe at the reduced temperature just sufficient to give a proper air circulation through the furnace to ensure a supply of the necessary amount of 20 oxygen to give good combustion.

Further objects are to provide an improved fuel saving device over those at present in use, and to utilize the said device as 25 a ventilator, to permit of readily cleaning and inspecting the several parts, and generally to adapt the said several parts to better perform the functions required of them.

With these and other objects in view, the 30 invention consists essentially of the improved construction particularly described and set forth in the following specification and accompanying drawing forming part of the application.

In the drawing:

Figure 1 is a side elevation partly in section of my improved furnace with casing cut away.

Figure 2 is a vertical section through my 40 improved device showing top of heater with opening therein.

Like characters of reference refer to like parts in the several figures.

Referring to the drawing:

15 A represents my improved furnace, comprising an outer casing 19, within which and in spaced relationship thereto is arranged a cylindrical heater 10 with feed and discharge openings 13 and 14 and in the top opening 17^a, fixedly secured on the heater 10. Also within the casing 19 and by means of a ring member 11, are outer and inner spaced chambers 15 and 16 respectively. The outer chamber 15 is provided with an 55 opening 17 registering with the opening 17^a in the heater top, whereby communication

is provided between the chamber 15 and the heater. Registering with this opening 17 is a heat distributing chamber 18 projecting into the inner chamber 16 and having 60 an inner closed end.

19 is the outer casing in spaced relationship to the member 10 and designed to insulate the same. 20 is an outlet in the upper wall of the chamber 15 communicating with the smoke conduit 21 extending through the outer casing 19. Adjacent to the top thereof and communicating with the inner chamber 16 are the heat distributing conduits 22 and 23, while 24 and 25 are 70 auxiliary heat distributing conduits extending from the top of the chamber 16 into the conduits 22 and 23 and designed to convey thereinto the superheated air from the top of the chamber 16.

26 is an air inlet conduit extending between the central conduit 17 and the inner wall of the chamber 16, the air being discharged from the chamber 16 through the conduits 22 and 23, and 24 and 25.

In a furnace of this construction, the products of combustion pass from the heater 12 upwardly through the opening 17 which is located above the central opening in the heater 12, and part of the products of combustion enter the conduit 18 while another stream passes around the annular passage way and up around the inner chamber 16 and is discharged through the smoke pipe 21.

Air is meantime being circulated through the pipe 26 into the chamber 16, and this air on its passage through the said chamber extracts heat units from the products of combustion which flow around the outer wall of said chamber, and the heated air 95 is delivered through the pipe 22 and pipe 23 to the room or rooms being heated, being previously superheated by the heated air from the auxiliary conduits 24 and 25.

The major part of the heat units enter 100 the chamber 18 and are retained for a sufficiently long time in contact with the wall of the chamber 16 to deliver their heat units to said chamber, and these heat units are picked up by the air passing through the 105 chamber in the manner above described.

In this way it will be seen that the heat units which formerly passed with the products of combustion into the smoke pipe are delivered and absorbed by the circulating 110 air to heat the house in which the heater is installed.

A proper circulation of air in the household is also obtained owing to the arrangement of the pipe 26.

As many changes could be made in the above construction, and many apparently widely different embodiments of my invention within the scope of the claims, constructed without departing from the spirit or scope thereof, it is intended that all matter contained in the accompanying specification and drawing shall be interpreted as illustrative and not in a limiting sense.

What I claim as my invention is:

1. A furnace of the class described, comprising an outer casing and a heater in spaced relationship, the heater having an opening in the top, heat distributing chambers arranged above the heater and communicating therewith and including an inner chamber and an outer chamber, an opening in the outer chamber designed to register with the opening in the heater top, a chamber projecting into the inner heating chamber formed with a closed end, said projecting chamber being designed to register with the opening in the outer chamber, an opening in the wall of the outer chamber connected to a smoke conduit, an air intake conduit for the inner chamber, heat distributing conduits for said inner chamber, and auxiliary heat distributing conduits connecting the top of the inner chamber with the aforementioned heat distributing conduits.
2. A furnace of the class described comprising a casing, a heater within the casing and in spaced relationship thereto, and

outer and an inner heating chamber in spaced relationship to one another arranged on the top of the heater, an opening in the outer heating chamber to receive the products of combustion from the heater, a superheating chamber projecting into the inner heating chamber and having a closed end, the outer end of said superheating chamber being open and designed to register with the opening in the outer heating chamber, conduits communicating with the inner heating chamber, heat distributing means for said conduits, super-heat distributing means connecting the inner heating chamber with the aforementioned distributing means, an air intake designed to form ventilating means for the inner heating chamber, and a smoke conduit connected with the outer heating chamber.

3. A furnace of the class described, comprising in combination an outer casing, a heater in said casing having an opening in the top, spaced heat distributing chambers communicating with said heater, the inner of said chambers being formed with an inwardly projecting chamber ending in a closed end, the open end of said projecting chamber being designed to register with an opening in the outer of said heat distributing chambers, heat conduits for the inner chambers, and auxiliary heat conduits for said chamber communicating with the aforementioned conduits whereby the heated air is discharged thereinto.

In witness whereof I have hereunto set my hand.

JOHN LONDEAU.
